Specification of Letters Patent.

Patented Aug. 6, 1918.

Application filed September 18, 1917. Serial No. 191,930.

To all whom it may concern:

Be it known that I, CHARLES FOSTER, a subject of the King of Great Britain, residing in Croydon, Surrey, England, have invented 5 certain new and useful Improvements in and Relating to Tabulating-Machines, of which the following is a specification.

This invention relates to improvements in and relating to tabulating machines.

10 It has already been proposed in the specification of British Letters Patent No. 2384 of 1915 to translate perforations in a card into alphabetical characters whereby groups of letters may be printed. In the case just 15 referred to a card is employed having a field in which a limited number of perforations may be formed representing letters of the alphabet arranged in a single column and which perforations, by means of one or more 20 additional perforations may be given a differential alphabetical meaning.

The present invention has for its object 25 to provide improved mechanism designed to be operated by a card such as that just above referred to and in which, as distinguished from the known mechanism, in place of a spring actuated type drum controlled by a swinging sector the position of which is controlled by the aforesaid card acting 30 upon settable stops, corresponding in number to the possible number of perforations in the alphabetical column, there is provided a swinging sector which sector itself carries the type, and is positioned by the settable stops. As in the prior case before referred to the settable stops may form part of 35 a machine constructed in accordance with specification of British Letters Patent No. 26896 of 1913, and the sector may be operated in the manner and by the same means 40 as the figure bearing sectors of the said machine.

In order, however, that the sector may accommodate the desired number of alphabetical characters, the number of possible 45 perforations in the alphabetical column of the card and the number of settable stops remaining the same, in accordance with this invention, the type carrying portion is elongated to twice or approximately twice its ordinary length, and provision is made 50 whereby either portion may be brought into the effective position.

In practice according to one form of the 55 invention a swinging sector is employed

constructed and operating substantially in the manner described in the aforesaid specification of British Letters Patent No. 26896 of 1913, said sector, however, being unprovided with teeth as it is not required to operate any counting mechanism. The sector just referred to is operatively associated with a second sector which corresponds substantially with the type sector of the aforesaid machine of the prior British Letters 60 Patent No. 26896 of 1913 except that it is extended in length as already stated and that provision is made whereby without affecting the normal swing of the said sector either the main or extended portions may be 65 brought into position so that the type hammer may act upon the selected type. The setting of the type sector is controlled by the first sector the movement of which in its turn is controlled by a series of settable 70 stops acting upon a stop on said first sector. The two sectors are latched together so that they swing as one, the latch being controlled by the settable stop, which in the earlier patent represents the zero stop. The zero 75 stop may in the present instance either be left blank or a letter may be placed on the sector at a point corresponding to this. The settable stops are in number equal to any possible perforation that may be formed in the 80 column in the card and may be twelve in number. The type sector is provided with a slot in which works a pin on the swinging sector, whereby the forward movement of the said type sector is limited. The latch 85 aforesaid may conveniently engage said pin so that when the said pin is engaged the forward part of the type sector may be brought into the operative position and when free of said latch and engaging the forward end of 90 its slot, the rear portion of the type sector 95 is in the operative position.

In order that the invention may be the better understood drawings are appended 100 illustrating the application of the invention to a machine of the type forming the subject of the aforesaid British Letters Patent No. 26896 of 1913. It will be understood that one alphabetical sector and its attendant mechanism will be required for each letter that is to be printed in line on the record at one time. Thus assuming the whole alphabet to be required 105 of such sectors would be employed. In practice, however, it is usually possible, when surnames are 110

by 52, with which is associated a platen 53, provided with an ink ribbon. As the construction and arrangement of the parts just referred to are all well known further description thereof is unnecessary.

As already explained, there are twelve possible positions for a perforation in each alphabetical column on the card and the character represented by each perforation is dependent not only upon its position in the said column but in the presence or absence of a perforation at the point indicated by the zero sign. Without a perforation at this point perforations at the points marked 10 1 to 11, represent the letters A to L, the letter I, serving also as J. With a perforation at the zero mark the significance of perforations at any one of the points 1 to 11 is altered and perforations at any one of the 15 said points now represent according to their positions the letters M to Y. The perforation at the zero point may also be utilized and in itself represent a letter, for example the letter Z. The type corresponding to the 20 respective letters of the alphabet are arranged upon the extension of sector 19 in the manner shown in Fig. 2 and they are each identified by the letter they represent. It is obvious however that the arrangement of 25 the type in the manner shown is quite optional and its arrangement may be raised in any manner desired, it being understood that the positions of the various perforations in the alphabet column of the card will 30 be correspondingly varied. As an example of the working of the invention it is assumed that it is desired to print the letter B. The perforation representing this letter is in the position 2 of the alphabet column see Fig. 6 35 and consequently the card when passing through the machine will raise the stop B as shown in Fig. 3. As the perforation at the zero point is absent, the raising of the B stop will simply free the sector from the 40 stop 20 so that when the restoring bar 40 is swung into its outer position the sectors being latched together will move as one and when arrested by the B stop the B type will be in the position ready to be impressed 45 upon the paper upon the operation of the hammer. The operation for any letter from A to L is the same the sectors being positioned by the appropriate stop. Assuming 50 that the letter N is to be printed. In this case a perforation is provided at the zero point see Fig. 7. Consequently as the card passes through the machine the zero stop is raised and contacting with the end of latch 55 30 raises the same and frees the sector which under the influence of its spring moves 60 slightly forward and as already explained carries the pin 28 clear of the latch. Simultaneously with the raising of the zero stop the stop which before represented the letter 65 B is raised and the sector is free to swing

outward until arrested by the said B stop. As the type sector is now free of the latch it will move forward until its movement is checked by the pin 28 reaching the end of slot 24 and when in this position the N type 70 will be in a position ready to be struck by the hammer. The position of the parts will then be as shown in Fig. 4. The operation will be the same for any of the letters N to Y the letters X and V being omitted, the 75 position of the sector being determined by the particular stop which has been raised. The letter L will be printed only if a perforation is formed in the zero position of the card without any other perforation in any 80 of the remaining positions in which case the type sector will swing to the full extent of its outward movement without any corresponding movement of the sector 22.

The parts in each case are restored after 85 the printing has been effected by the restoring bar. It will thus be seen that by means of the arrangement according to this invention I am enabled to effect the printing of practically the whole of the alphabet without unduly increasing either the number of stops or employing a number of perforations beyond the limits of the column of an ordinary card. It will be understood 90 that the cards will be provided with a number of alphabet columns equal to the number of letters it is desired to use. Thus supposing surnames are to be printed the number of columns provided would be equal to the number of the letters required for the 100 longest name. Assuming that 9 letters is the contemplated maximum number then only 9 letter columns would be provided.

While I have described the invention as particularly designed for the translation of 105 perforations into alphabetical characters, it may be advantageously employed for the production of any other ciphers or numerals and it may with particular advantage be employed to reduce the number of columns 110 necessitated where very large amounts are to be indicated. For example for tens of thousands up to a known amount say 20,000.

In machines as ordinarily constructed it would be necessary to employ four columns 115 upon the cards and four sectors to print values up to 9,000, and five columns and five sectors for an amount up to 20,000. By providing the sectors arranged in accordance with this invention with type representing compound members it is possible by employing only four sectors to accomplish results which as above explained under ordinary circumstances require five columns 120 and five sectors. Thus for example instead of the alphabetical type, figure types would be employed representing 1 to 20 or there-over according to the number of type which would be carried by the sector. Obviously 125 the arrangement and construction of the 130

extensions upon the sectors may be varied as may be found in practice to be necessary or desirable.

Claims:

5. 1. In a tabulating machine operated by a perforated card a swinging type bearing member having a number of type thereon greater in number than the number of possible perforations in a column of the card 10 and means operated by said card to position the swinging member to bring the desired type into the printing position.
2. In a tabulating machine operated by a perforated card a swinging type bearing member having a number of type thereon greater in number than the number of possible perforations in a column of the card, a second swinging member controlling the movement of the type sector, means for connecting said sectors, and means operated by said card to release the swinging type bearing member to permit its adjustment to bring the desired type into the printing position. 15
25. 3. In a tabulating machine operated by a perforated card, a swinging type bearing member having a number of type thereon greater in number than the number of possible perforations in the column in the card, a second swinging member, stops set by the card for positioning said second member a connection between the type bearing member and the second swinging member and means for disconnecting said type bearing 30 member from the swinging member controlled by the card whereby the said type bearing member is free to move independently of its controlling member in order to bring the desired type into the printing position.
40. 4. In a tabulating machine operated by a perforated card a swinging type bearing member having a number of type thereon greater in number than the number of possible perforations in the column of the card, a second swinging member, stops controlled by the card for positioning said second swinging member, a spring controlled latch upon the second swinging member, a stud upon the 45 type bearing member engaging said latch and means controlled by the card for releasing said latch whereby it may be positioned independently of the second swinging member to bring the desired type into the printing position.
50. 5. In a tabulating machine operated by a perforated card a swinging type bearing member having a number of type thereon greater in number than the number of possible perforations in the column of the card, a second swinging member, stops controlled by the card for positioning said second swinging member, a stud upon the type bearing member engaging said latch and means controlled by the card for releasing said latch whereby it may be positioned independently of the second swinging member to bring the desired type into the printing position.
55. 6. In a tabulating machine operated by a perforated card a swinging type bearing member having a number of type thereon greater in number than the number of possible perforations in the column of the card, a second swinging member, stops controlled by the card for positioning said second swinging member, a stud upon the type bearing member engaging said latch and means controlled by the card for releasing said latch whereby it may be positioned independently of the second swinging member to bring the desired type into the printing position, and means for giving a slight initial movement to the type bearing member whereby the accidental reengagement of the latch before the operation of the type bearing sector is avoided. 60
7. In a tabulating machine operated by a perforated card a swinging type bearing member having a number of type thereon greater in number than the number of possible perforations in the column of the card, a second swinging member, stops controlled by the card for positioning said second swinging member, a spring controlled latch upon the second swinging member, a slot in the second swinging member a stud on the type bearing member projecting through 65 said slot and engaging said latch whereby it may be positioned independently of the second swinging member to bring the desired type into the printing position.
80. 8. In a tabulating machine operated by a perforated card a swinging type bearing member having a number of type thereon greater in number than the number of possible perforations in the column of the card, a second swinging member, stops controlled by the card for positioning said second swinging member, a spring controlled latch upon the second swinging member, a slot in the second swinging member a stud on the type bearing member projecting through 85 said slot and engaging said latch whereby it may be positioned independently of the second swinging member to bring the desired type into the printing position.
85. 9. In a tabulating machine operated by a perforated card a swinging type bearing member having a number of type thereon greater in number than the number of possible perforations in the column of the card, a second swinging member, stops controlled by the card for positioning said second swinging member, a spring controlled latch upon the second swinging member, a slot in the second swinging member a stud on the type bearing member projecting through 90 said slot and engaging said latch whereby it may be positioned independently of the second swinging member to bring the desired type into the printing position, and means for giving a slight initial movement to the type bearing member whereby the accidental reengagement of the latch before the operation of the type bearing sector is avoided. 95
100. 10. In a tabulating machine operated by a perforated card a swinging type bearing member having a number of type thereon greater in number than the number of possible perforations in the column of the card, a second swinging member, stops controlled by the card for positioning said second swinging member, a spring controlled latch upon the second swinging member, a slot in the second swinging member a stud on the type bearing member projecting through 105 said slot and engaging said latch whereby it may be positioned independently of the second swinging member to bring the desired type into the printing position, and means for giving a slight initial movement to the type bearing member whereby the accidental reengagement of the latch before the operation of the type bearing sector is avoided.
110. In testimony whereof I affix my signature in the presence of two witnesses.

CHARLES FOSTER.
